APPARATUS FOR OBTAINING MARBLING EFFECT ON PAPER

Application filed December 29, 1924, Serial No. 758,632. Renewed December 28, 1928.

This invention relates to improvements in apparatus for ornamenting or decorating the surface of material such as a sheet or web of paper or the like.

5 The apparatus comprising my invention will be found capable of broad application wherever it is desired to ornament or decorate various materials, whether in sheet, web or other form, and will be disclosed with particular reference to its adaptability to the 10 art of decorating or ornamenting paper, such a disclosure of the invention being deemed adequate to enable those skilled in the art to practice the invention in connection with any 15 other material.

The art of ornamenting or decorating paper includes numerous and various processes which may be for convenience arranged in three classes, namely,—decorating finished 20 paper by coating, printing or embossing; secondly, coloring and treating paper stock during manufacture; and thirdly, by rolling a sheet of paper upon the surface of a liquid, such as water, which carries coloring pig- 25 ments in the form of an irregular design upon its surface. These methods, above enumerated, however, offer many disadvantages for the following reasons. The first produces 30 designs that are regular in appearance and that are exactly repeated; the second has definite limitations as to the character of ornamentation which may be applied; and the third, heretofore chiefly used in producing what is known as a marbling effect, has limitations both as to quantity production and 35 more particularly with respect to the reproduction at different times of a design having the same general appearance.

The present invention deals with improvements in the apparatus for ornamenting a material such as paper according to the third process enumerated above, and accordingly it is an object of my invention to provide an apparatus whereby a continuous web of 45 paper may be ornamented or decorated by a design or pattern that is uniform in its general aspect although in specific detail is never exactly the same.

Considered broadly, this is accomplished 50 by a very definite control of the devices and

apparatus for formulating the design on the float carrier or body of water,—that is, by distributing known quantities of predetermined colors in definite areas upon said water surface, and by controlling the elapsed time 55 for said colors to spread in irregular outline before application to the paper, all of which takes place in the manner of a continuous cycle to give the effect of a similar but ever changing design. A distinct advantage of 60 the method thus employed consists in the possibility of adopting definite formulas for different designs which, when adhered to, will reproduce any particular design at various times. Of course, it is to be understood that 65 the exact detail of any particular design will not be reproduced but the general appearance with respect to color values, tone, approximate similitude of outline, etc., can be duplicated with enough exactness to produce 70 the same general impression on the observer. The value of thus being able to reproduce from time to time designs of this character having the same general appearance, will be appreciated when it is considered that the 75 market for decorative papers includes many purchasers who, having adopted some particular design as a dress for merchandise, naturally desire to maintain the same as a distinctive characteristic of their product for 80 a considerable period and can only do so when it is possible to re-order the same design as previously used.

A further object of the invention is the provision of apparatus capable of applying the 85 design to a continuous web of paper led from a roll, as distinguished from handling the paper in separate sheets whereby a volume and economy of production may be attained on a commercial scale which would be quite 90 impossible under the hand methods heretofore practiced.

Other objects and advantages will be apparent from the following description and accompanying drawings, in which one form of an apparatus capable of practicing the invention is illustrated.

In the drawings:—

Fig. 1 is a diagrammatic sectional eleva- 100

tional view of an apparatus embodying certain features of my invention;

Fig. 2 is a partial plan view taken on the line 2—2 of Fig. 1;

Fig. 3 is a sectional elevational view through one of the color feeding mechanisms taken on the line 3—3 of Fig. 2;

Fig. 4 is a plan view of the same;

Fig. 5 is a perspective view of one of the color scrapers;

Fig. 6 is an enlarged plan view of one of the color distributing members or discs;

Fig. 7 is an elevational sectional view on the line 7—7 of Fig. 1; and

Fig. 8 is a detail view of the adjustable speed drive for the contact drum.

Generally, the apparatus may comprise a movable trough or tank 1 for containing a liquid or float carrier such as water, one or more mechanisms 2 for distributing color materials on the surface of the water to form a design, a contact drum 3 for effecting a rolling contact between a continuous web of paper P and the surface of the water to take up therefrom the color material constituting the design and a take up and drying mechanism 4 for winding up and drying the decorated paper web.

In detail, the tank 1, only part of which is shown, may take the form of a U-shaped trough, as shown in section in Fig. 7, which is endless or circular in shape and which is supported by wheels 5 that ride upon a circular track comprised of the rails 6. The tank is preferably adapted for a rotative movement and may be driven by any suitable means and at any speed desired, by suitable mechanism not necessary to show. An appropriate liquid carrier of suitable composition well known in the art for carrying a liquid color material in flotation upon its surface without mixing therewith is contained in the tank and the level thereof may be maintained constant by suitable means (not shown). It will be understood that the speed of rotation of the tank may be varied as may be found desirable or necessary to cooperate with the other units of the apparatus. A frame F may extend along either side of the tank for supporting various parts of the apparatus later to be described.

As is well known in the art, various liquid color materials are obtainable which are insoluble in water or other liquid of the proper chemical characteristics and which may be used as the carrier for the various colors to be employed. The liquid carrier is contained in the tank or trough 1 and maintained at a fixed level by suitable means (not shown). The color materials hereafter termed merely "colors" are carried in flotation upon the surface of said carrier and may be so chemically constituted that they will not readily mix with one another nor with the liquid car-

rier, but will be readily taken up by the paper to be ornamented as hereinafter described.

A unitary assembly of devices herein designated as 2 is located above the rotating tank and, as shown, comprises color distributors in the form of one or more discs D which are rotatable about vertical axes. Shafts 8 carry the distributors D and are rotatable in bearings 10 fixed to transverse bars 11 and have bevel gears 12 fixed to their upper ends that mesh with bevel driving gears 13 fixed to a driving shaft 14. The driving shaft 14 extends transversely of the tank and is rotatably supported at either side thereof in bearing brackets 15 secured to the frames F. A cone pulley 16, secured to the shaft 14, may be driven from a similar cone pulley 17 of a transverse driving shaft 18, located below the tank. The cone pulleys afford a means of varying the speed of the shaft 14 as is desirable for rotating the distributors at various speeds for the purpose as will presently appear. Other mechanism, however, such as a variable speed transmission, may be employed for controlling and varying the speed of the shaft 14 and the driving shaft 18 may receive its power from any suitable source.

The distributors D are preferably in the form shown in Fig. 6 and, as will be seen, comprise a disc having its periphery formed of different portions converging to a plurality of points 21, 22, 23, etc., which act as discharge points for the color. Each disc receives on its upper surface a stream of color which, as shown, may be constant and uniform in its flow from a color reservoir and, as the disc rotates, the color carried thereby is thrown outwardly from the discharge points by centrifugal force in the form of drops that are distributed upon the surface of the liquid carrier.

The discharge points of the distributors may be of different lengths and at various distances from the axis of rotation, so as to distribute the drops of color more or less uniformly across the moving sheet of liquid beneath the same. The size of the discharged drops of color and their distribution throughout the width of the liquid carrier moving beneath the distributors may be very accurately controlled by the speed of rotation of said discs and the size, shape and length of said discharge points. By length of discharge points is meant the distance thereof from the axis of rotation of the disc. Further factors determining the size of color drops discharged are, of course, the viscosity of the color and the rate of feed thereof to the distributors. This latter may also be accurately controlled by the means now to be described.

Each distributor disc receives its supply of color from a supply tube 25 that is inclined to have its lower delivery end located adjacent the shaft 8 or near the axis of the disc. A color reservoir 26 supported on one of the

transverse bars 11 and adjacent its disc contains a supply of color. A rotating feed roll 27 is mounted to partially dip into the color of the reservoir and has in scraping contact therewith a scraper or blade 28 carried by the upper end of the delivery tube 25. As the roll 27 rotates in the direction of the arrow (see Fig. 3), the color taken up by the roll 27 is scraped from the periphery of the roll 10 by the scraper and flows down the supply pipe 25 and on to the distributor disc. A transverse driving shaft 29, preferably located above the color reservoir, is belted to the roll 27 of the reservoir by means of the pulleys 15 30 and 31, whereby the roll may be continuously driven at a constant predetermined speed. A cone pulley 32, carried by the end of the shaft 29, is driven by means of a belt 33 in engagement with a similar cone pulley 20 34 fixed to the driving shaft 18, and provides means for varying and controlling the speed of the roll 27 whereby a greater or less amount of color will be presented for the scraping action of the blade 28.

25 An agitator or stirrer is provided in the color reservoir comprising blades 36 for engaging the wall of the reservoir which are pivoted, as shown in Fig. 3, to levers 37 rock- 30 ing loosely on the shaft of the roll 27. One of said levers 37 extends upwardly as at 39 and is connected to a connecting rod 40 of the strap of an eccentric 41 fixed upon the shaft 29. A cross bar 38 connects the levers 37 below the roll 27 and is provided with openings 35 as shown to allow a free flow of color therethrough to eliminate resistance as the levers and bar are rocked back and forth by the eccentric. During this movement, the blades 36 bear upon the cylindrical or curved surface 40 of the reservoir to remove the color therefrom and to agitate the same, whereby the color is kept mixed and in uniform consistency. There may be any number of distributors and color reservoirs employed and they may be ar- 45 ranged singly or in sets of two or more, their number and arrangement will depend to a large extent on the color arrangement that is required for producing the pattern or design desired. Color is, by the above described 50 means, deposited on the surface of the liquid carrier during the movement of the tank to the right (viewing Fig. 1) which eventually brings the deposited color to a point where the surface of the liquid carrier is brought 55 into a rolling contact with the web of paper P carried by the drum 3.

A rake 48, having a plurality of depending prongs 49, is supported by arms 50 carried on a shaft 50' which is both pivoted and slidable 60 transversely in the frames F at either side of the tank. The arms 50 may be swung up and down to position the rake either out of or in the path of the color carried by the liquid, to rake out or elongate the color design when 65 desired. Also a slight reciprocatory move-

ment may be given to the shaft 50' by means not shown to still further vary the design to be applied to the paper.

A fan or blower 56 may also be mounted as shown, which may be rotated by a belt pulley 57 and functions in its rotative movement to exert a light pressure of air upon the liquid and color carried thereby to spread or fan out the color as may be desired, and according to its speed will spread the color to any desired 75 extent.

During the travel of the tank from beneath the distributing devices at 2, where the color has been deposited upon the liquid carrier, to the contact drum 3, the design of the deposited color will modify itself somewhat irregularly which may be accentuated by the fan 56 and rake 48 when desired and the extent of said modification in the design is largely determined by the traveling speed of said tank 80 1,—in other words, by the length of time allowed for said colors to spread on the liquid carrier before being taken up by the paper. The color values in said design, although 85 irregularly distributed, will be substantially uniform as determined by the distributing devices at 2.

The web of paper to which the color design is to be transferred is, as shown in Fig. 1, led off from a supply roll S in the direction 95 of the arrows, over suitable guide rolls to and partially around first the upper drum 3' and then partially around the lower contact drum 3 so as to come into contact with the surface of the liquid carrier. Then it travels upwardly, as shown, over guide roll 42, belt carrier 42', guide roll 43, around driving drums 44 and 45, and finally off to a suitable take-up roll (not shown). An important feature of the present improvement is the provision of 100 means to insure positive control of the travel of the paper web in its contact with the surface of the moving liquid carrier. It may be desired to have the paper web travel at exactly the same speed as the surface speed of 105 the liquid carrier with which it comes into contact, i. e., a perfect rolling contact, or it may be desired to have the paper travel at a slightly greater or slightly less speed than the moving liquid carrier to cause certain 110 distortional effects of the design when taken up. For this purpose, the shaft 61 of the contact drum 3 is mounted in adjustable bearings, indicated at 60, so that it may be adjusted to bring the paper web into proper 115 register with the surface of the liquid carrier. The shaft 61 of said contact drum 3 is positively driven by means such as shown in Fig. 8 so that its speed of rotation may be adjusted. The devices for effecting this change 120 of rotative speed of said shaft 61 are of well known character consisting of adjustable cone pulleys 62, belt 63 driven from source of power as at 64. Mounted above 125 the contact drum 3 is the idler drum 3' which 130

bears under its own weight upon the drum 3 having its shaft 65 mounted in a vertically guided bearing 66 for this purpose. The paper web P being carried partially around said idler drum 3' and between the nip of said drum upon the lower contact drum 3 and then partially around the latter, as shown, is very firmly gripped for positively controlled travel with said drums 3' and 3 irrespective of any variation in tension upon said paper web due to the take-up roll or the let-off roll S. In this way, the travel of the web P in contact with the surface of the liquid carrier is definitely determined by the peripheral speed of said contact drum 3.

A blower 46, in the form of a pipe, is located above the roll 3' and has a delivery nozzle in a side thereof. The blower is disposed so as to have its delivery nozzle port 20 closely adjacent but not in contact with the paper web carrying the design and is arranged to deliver an air blast to the ornamented surface of the web. The air may be of any desired temperature and acts as a barrier to the upward travel of any liquid, in addition to the color, which may adhere to the web and also helps to dry out the web preparatory to its being received by the drier drums. The blower nozzle, not being in contact with the web, will not disturb the color design deposited thereon but only tends to drive back surplus liquid or moisture. Above the blower and contacting with the unornamented side of the web is preferably mounted a guide 47 which tends to keep the web in flattened condition as it is led to the roll 42.

In the event that all the coloring carried by the liquid is not taken up by the web of paper, and in order to scavenge the liquid of any such surplus color preparatory to the re-deposit of color thereon during the continued rotation of the tank, I provide the following means. A winding shaft 500 located at the right of the roll 3 is rotatably mounted above the tank and is actuated preferably in a step by step movement by means of a ratchet wheel 59 and a ratchet 52 carried on a lever 53. The lever 53 is oscillated by means of a rod 54 connected to an eccentric (not shown) or by other operating means carried by the shaft of the roll 3. A let off drum 55 extending transversely across the tank and located thereabove, is adapted to supply a web of paper for being wound up by the shaft 500. The roll of paper wound on shaft 500 is of such width as to extend entirely across the tank and the paper employed preferably has such characteristics as will render it capable of readily absorbing any surplus color that may be carried by the liquid and that is not taken up by the web P.

It will be observed that various units may be operated at various speeds that are variable independently of one another whereby

the apparatus is adapted for unlimited adjustment to thereby produce designs of numerous forms and that by a proper tabulation of the relative speeds of various units and suitable data as to the quantity and color of the design creating materials, it is possible to again reproduce any design that has been previously produced.

Also, since the speed of the units is independently variable, it is therefore possible to control to a nicety the operation of the apparatus, whereby a continuously moving web of paper may be ornamented with consecutive designs that are similar only in general appearance while in detail the designs are not duplicated in exactness to such an extent as to impair the effect of their general similarity.

Many changes may be made in the apparatus shown to adapt it for other uses without departing from the invention, and we therefore prefer not to be limited by the foregoing disclosure, but rather by the following wherein I claim:

1. A device for distributing color upon a surface, comprising a rotating disc mounted substantially parallel with said surface, a color supply and means for feeding color therefrom to said disk within its periphery so that said color will be discharged from said disc upon said surface by centrifugal force.

2. A device for distributing color upon a surface, comprising a rotating disc mounted substantially parallel with said surface and having peripheral discharge points at different distances from its axis, a color supply and means for feeding color therefrom to said disc within its periphery so that said color will be discharged upon said surface by centrifugal force.

3. A device for distributing color upon a surface, comprising a rotating disc having its periphery formed of portions with sides converging to points at various distances from the axis of said disc a color supply and means for feeding color therefrom to said disc within its periphery so that said color will be discharged upon said surface from said points by centrifugal force.

4. The combination with a device for distributing color upon a surface, comprising a rotating disc, of means for supplying color to said disc in a regulatable quantity comprising a feed roll dipping in a supply of color and a scraper bearing upon said roll and directing the color therefrom and onto said disc.

5. The combination with a device for distributing color to a surface comprising a rotating disc, of means for feeding color to said disc, comprising a color reservoir and a feed roll dipping in said reservoir, an agitator to stir the color in said reservoir and a scraper bearing upon said feed roll and directing the color therefrom to said distributing disc.

6. In an apparatus for ornamenting a web of material in which a traveling body of liquid is employed in a continuous cycle for carrying color deposited upon its surface, the combination thereof, with means for effecting a rolling contact between said web of material and the surface of said liquid whereby said web will take up some of the color therefrom, and means acting subsequently thereto for removing the remainder of the color from said liquid comprising a roll of color absorbing material rotating in contact with the surface of said liquid. 70 75
- 10 7. In an apparatus for ornamenting a web of material in which a traveling body of liquid is employed in a continuous cycle for carrying color deposited upon its surface, the combination thereof with means for effecting a rolling contact between said web of material and the surface of said liquid whereby said web will take up some of the color therefrom, and means acting subsequently thereto for removing the remainder of the color from said liquid comprising a winding roll of color absorbing material rotating in contact with the surface of said liquid, and a let off roll of color absorbing material for supplying said winding roll. 80 85 90

- same whereby said web will be positively carried into and out of contact with the surface of said liquid carrier for the purpose described.
- 5 14. In an apparatus for ornamenting a web of material in which a traveling body of liquid is employed for carrying color deposited upon its surface, means for causing said web to take up color from the surface of said liquid carrier comprising a pair of drums 70 rotating in peripheral contact under pressure, one of said drums being adjustably mounted to have its periphery closely adjacent the surface of said liquid carrier, the course of said web being partially around each drum and between the nip of the same whereby said web will be positively carried into and out of contact with the surface of said liquid carrier for the purpose described.
- 10 15. In an apparatus for ornamenting a web of material in which a traveling body of liquid is employed for carrying color deposited upon its surface, means for causing said web to take up color from the surface of said liquid carrier comprising a pair of drums 75 rotating in peripheral contact under pressure, driving means for said drums arranged to adjust the speed thereof, one of said drums having its periphery closely adjacent the surface of said liquid carrier, the course of said web being partially around each drum and between the nip of the same whereby said web will be positively carried into and out of contact with the surface of said liquid carrier for the purpose described.
- 15 16. A device for distributing color upon a surface, comprising a rotating, irregularly star-shaped disk and means for feeding color to said disk within its periphery.
- 20 17. In an apparatus for ornamenting a web of material in which the color is supplied to the web by tangential contact with a body of carrier liquid, the combination thereof with a device for distributing color upon the surface of the carrier liquid comprising a supply 80 for delivering a stream of color, and means for subdividing the stream into particles and projecting said particles along trajectories radiating initially in a plane parallel to and spaced from the surface of the carrier liquid.
- 25 18. In an apparatus for ornamenting a web of material in which the color is supplied to the web by tangential contact with the surface of a body of carrier liquid, the combination thereof with a device for distributing 85 color upon the surface of the carrier liquid comprising a supply for delivering a stream of color, and a color carrying device having a plurality of localized color discharge areas, each localized area being constrained for motion in a predetermined path at a predetermined speed to discharge color therefrom by centrifugal force and thereby to subdivide the color into drops under definite and repeatable conditions, and projecting said particles along trajectories radiating initially in a plane parallel to and spaced from the surface of the carrier liquid.
- 30 19. In an apparatus for ornamenting a web of material in which the color is supplied to the web by tangential contact with a body of carrier liquid, the combination thereof with a device for distributing color upon the surface of the carrier liquid comprising a supply for delivering a stream of color, and a color carrying device having a plurality of localized color discharge areas, each localized area being constrained for motion in a predetermined path at a predetermined speed to discharge color therefrom by centrifugal force and thereby to subdivide the color into drops under definite and repeatable conditions, and projecting said particles along trajectories radiating initially in a plane parallel to and spaced from the surface of the carrier liquid.
- 35 20. In an apparatus for ornamenting a web of material in which the color is supplied to the web by tangential contact with a body of carrier liquid, the combination thereof with a plurality of supplies each delivering a stream of a particular color, and a color carrying device associated with each of said supplies for receiving color therefrom, each device having a plurality of localized color discharge areas, each localized area being constrained for motion in a predetermined path at a predetermined speed to discharge color therefrom by centrifugal force and thereby to subdivide the color into drops under definite and repeatable conditions.
